UNITED STATES PATENT OFFICE.

FREDERICK W. NITTEL, OF ATTLEBORO FALLS, MASSACHUSETTS, ASSIGNOR TO M S CO.,
OF ATTLEBORO, MASSACHUSETTS.

WATCH-BRACELET END HOOK.

Application filed August 5, 1927. Serial No. 210,831.

This invention relates to certain new and useful improvements in watch bracelet hooks, and the primary object thereof is to provide a novel form of spring latch which 5 may be produced by doubling a piece of spring material.

A further object of the invention is to provide a latch which may be operated from either side of the hook thereby to enable the 10 hook to be easily and quickly applied to and removed from the watch.

The invention further aims to provide a latch of this kind in which the doubling of the spring metal affords a spring catch to 15 hold the latch against accidental opening movement.

In the drawings:—

Figure 1 is a top plan view of the invention, and
20 Figures 2, 3 and 4 are sections on lines 2—2, 3—3 and 4—4 respectively of Figure 1.

In proceeding in accordance with the present invention, the hook is formed of a piece of metal to provide a back 1, an end 25 wall 2, a front 3 and a tongue 4, which latter is spaced from the back 3 to provide an opening 5 into which the usual loop on the side of the watch can be introduced. The tongue 4 at its free end is provided with a 30 depressed part 6 which is of concavo-convex cross section as shown in Figure 4. The latch is formed of a piece of spring material doubled upon itself to provide opposed legs 35 7 and 8, the latch being received between the back 1 and the front 3 and being pivotally connected to the latter parts by means of a pivot pin or rivet 9. As shown in Figure 4, the leg 8 of the latch is offset at its free end and is formed of concavo-convex cross section as indicated at 10 so as to receive the 40 convex side of the keeper 6 in its concave side. The sides of the leg 7 of the latch have extensions that are turned at right angles to provide sides 11 which lie flush with the back 1 and the front 3 as shown in Figure 45 3. The free end of the leg 8 of the latch is formed at its opposite sides with finger nail receiving cut outs 12 which latter project outwardly from the free end of the tongue 50 4 so that the latch can be manipulated from either side of the tongue.

From the foregoing it will be seen that due to the spring properties of the metal of which the latch is formed and due to the

spring properties of the tongue 4, the offset or struck out parts 6 and 10 can freely snap or ride one over the other so as to enable the latch to be moved to latched or unlatched position. It will further be noted that the entire device is composed of but 55 60 three parts, which can be economically produced and assembled by mere heading of the rivet.

It will be also noted that the front ends of the sides 11 will engage the usual bar 65 at the side of the watch and prevent same from entering the latch.

Having thus described my invention what I claim as new and desire to secure by Letters Patent is:—

1. In a watch bracelet hook, a hook member having a back, a hook on one end of the back having a concavo-convex part at its free end, a front, a U-shaped spring latch member in the hook member having the free end of one of its legs offset to engage the hook and provided with a concavo-convex part to engage the concavo-convex part of the hook, and a rivet pivotally connecting the latch to the hook member, the latch having 70 75 extensions on one of its legs bent inwardly toward the other leg to form sides and having finger-nail receiving depressions on opposite sides of said offset free end thereof.

2. In a watch bracelet hook, a hook member having a back, a hook on one end of the back having a concavo-convex part at its free end, a front, a U-shaped spring latch member in the hook member having the free end of one of its legs offset to engage the hook and provided with a concavo-convex part to engage the concavo-convex part of the hook, and a rivet pivotally connecting the latch to the hook member.

3. In a device of the type set forth, a hook member having a back provided with a hook on one end thereof and having a front which latter has an end spaced from the hook, and a latch disposed between the back and front and extending across the space between the hook and said end of the front and engaged with the inner face of the hook, and means to pivotally connect the latch to the member.

4. In a device of the type set forth, a hook member having a back provided with a hook on one end thereof and having a

front which latter has an end spaced from the hook, and a latch disposed between the back and front and extending across the space between the hook and said end of the front and engaged with the inner face of the hook, means to pivotally connect the latch to the member, and means to latch the latch to the hook.

5. In a device of the type set forth, a hook member having a back provided with a hook on one end thereof and having a front which latter has an end spaced from the hook, and a latch disposed between the back and front and extending across the space between the hook and said end of the front and engaged with the inner face of the hook, said latch being of substantially U-shape and having extensions on one of its legs bent inwardly toward the other leg to 15 form sides, and means to pivotally connect the latch to the member.

6. In combination with a member having a back, a hook and a front having its forward end spaced from the hook to receive a wrist watch bar or the like in such space, 20 a latch between the front and back having a part extending across said space and en-

gaged with the hook, and means to movably connect the latch to the member.

7. In combination with a member having a back, a hook and a front having its forward end spaced from the hook to receive a wrist watch bar or the like in such space, 30 a latch between the front and back having a resilient part extending across said space and engaged with the hook, means on the hook to engage said resilient part so as to latch the latch, and means to movably connect the latch to the member.

8. In combination with a member having a back, a hook and a front having its forward end spaced from the hook to receive a wrist watch bar or the like in such space, 35 a latch between the front and back having a part extending across said space and engaged with the hook, one of the last named elements being resilient and said elements having complementary latching means, and means to movably connect the latch to the member.

In testimony whereof I have signed my name to this specification.

FREDERICK W. NITTEL.
